United States Patent

Des. 237,857
Patented Dec. 2, 1975

237,857

ANDIRON

James W. Welch, P.O. Box 455,
Lake Stevens, Wash. 98258

Filed May 15, 1974, Ser. No. 470,178

Term of patent 7 years

Int. Cl. D7—08

U.S. Cl. D7—211

FIG. 1 is a top perspective view of an andiron showing my new design.

FIG. 2 is a side elevational view thereof.

FIG. 3 is a front elevational view thereof.

FIG. 4 is a rear elevational view thereof; and

FIG. 5 is a top plan view thereof.

I claim:

The ornamental design for an andiron, substantially as shown.
